UNITED STATES PATENT OFFICE.

BENJAMIN MARSH AND FREDERICK W. HOFFMAN, OF ALBANY, NEW YORK.

DESIGN FOR A SPOON.

SPECIFICATION forming part of Design No. 20,923, dated July 7, 1891.

Application filed January 27, 1891. Serial No. 379,315. Term of patent 7 years.

To all whom it may concern:

Be it known that we, BENJAMIN MARSH and FREDERICK W. HOFFMAN, citizens of the United States, residing at Albany, in the county of Albany and State of New York, have invented and produced a new and original Design for Handles of Spoons, of which the following is a specification, reference being had to the accompanying drawing, forming a part thereof.

The drawing illustrates our new design for a spoon.

The leading feature of our design consists in the figure *a* of a man in the dress of a Knickerbocker, in which he is represented as being attired in leggins, short breeches, short coat, Vandyke ruff or cape, and a broad-brimmed and high-crowned hat. With this figure of the man is represented the figure of

a chair on which the man is seated, with his right hand holding a pipe and his left hand holding a mug. If desired, either the pipe or mug, or both, may be omitted. In the background is a figure representing a side jamb of a fire-place and a portion of a mantel, both of which may be omitted, as they are not essential in this design.

What we claim is—

The design for a handle of a spoon herein shown and described, the same comprising the figure of a man attired as a Knickerbocker and seated sidewise on a chair, and a figure of a jamb of a fire-place, as set forth.

BENJAMIN MARSH.

FREDERICK W. HOFFMAN.
